(57) **CLAIM**

The ornamental design for exterior features for an automobile, as shown and described.

DESCRIPTION

FIG. 1 is a perspective view of exterior features for an automobile embodying the invention.

FIG. 2 is a top view of the design shown in FIG. 1.

FIG. 3 is a side view of the design shown in FIG. 1.

FIG. 4 is a front view of the design shown in FIG. 1; and, FIG. 5 is a rear view of the design shown in FIG. 1.

The side view opposite the side illustrated in FIG. 3 is a mirror image of FIG. 3. The broken line showing of the environment is for illustrative purposes only and forms no part of the claimed design. The bottom view is not part of the claimed design.
